MAGNETIC TAPE DUPLICATOR

Darrel A. Lauer, San Mateo, Calif., assignor to Ampex Corporation, Redwood City, Calif.

Filed Mar. 29, 1971, Ser. No. 129,298

Term of patent 14 years

Int. Cl. D14—01

U.S. Cl. D26—14

The sole figure is a front, top and right side perspective view of a magnetic tape duplicator showing my new design, the left side and back being mirror images of the right side and the front, respectively, and the bottom being conventionally plain.

I claim:

The ornamental design for a magnetic tape duplicator, substantially as shown and described.
